TRACK JOINT LUBRICATION

Frank W. Brooke, Pittsburgh, Pa.

Application November 19, 1947, Serial No. 786,961

4 Claims. (Cl. 238—161.5)

1

This invention is an improvement in rail joints, of the standard type or class in common use on railroads. It has in view to provide the joint, within the lengthwise and vertical zones defined by the extent of the usual rail-connecting fish plates, with means for lubricating otherwise exposed surfaces, of the rails, the fish plates, and bolts, for prevention of corrosion.

Also, to provide for vertical or lateral flow disposal of any water or moisture finding its way between the ends of the rails themselves.

As is well known, centers of moisture may begin and rapidly progress the corrosion of steel, and tend to increase more rapidly in locations of stresses. Also, that the combination of stresses and corrosion may and do cause fractures in such steel members as rail ends, under the usual service strains.

As is well known also, rail joint service is very severe, subject to all weather conditions, and the usual up and down movement of the rail ends, even when connected by the tie plates or fish bars.

The rail ends, for practical reasons, cannot be at all times tightly butted together, under varying extreme temperatures, of say from 105° F. to -10° F. below zero. Hence, it is not unusual to provide or allow for transverse spacing of $\frac{1}{8}$ " to $\frac{3}{16}$ ", more or less, and thus open to entrance of moisture, rain, or melted snow or ice.

To meet such conditions, my invention provides for proper placement of lubricant containing sections or packing units of compressible or resilient and moisture-repellant character, to permit slight relative movement between the rail end portions and the fish plates. Such means are susceptible of such relative movement, without effecting efficiency of the joint as a whole.

In order to retain such unitary lubricating members or packing units in proper positions, they are not only held by the usual transverse bolts of the joint, but are also resisted against endwise movement by means of retaining blocks or bodies located beyond the outer ends of the lubricating members and between the ends of the fish plates and rail web, and also across the transverse gap or space between the rail ends, and acting as movement preventing dams.

Heretofore, various more or less similar means have been provided to effect track joint lubrication, but all such are of limited efficiency in preventing leakage and resulting corrosion of the several metal surfaces of the entire joint. At times such corrosion may result in failure and resulting wrecks and damage.

2

A preferred embodiment of my invention is illustrated in the accompanying drawings, in which:

Fig. 1 is a view of the rail joint in side elevation, partly broken away.

Fig. 2 is a transverse horizontal section on the line II—II of Fig. 1.

Fig. 3 is a cross section on the line III—III of Fig. 1.

Fig. 4 is a cross section on the line IV—IV of Fig. 1.

Fig. 5 is a cross section on the line V—V of Fig. 1.

Fig. 6 is a detail view of one of the retaining rods or wires.

Fig. 7 is an isometric end view of one form of lubricating unit.

Fig. 8 is an isometric end view of a similar unit, of different form.

20 The members of the rail joint are of conventional standard construction, and illustrate the main rails as provided with the usual head 2, central web 3 and flanges 4, 4, supported upon and secured to the usual spaced apart ties 5.

25 At each opposite side of adjacent end sections of the rails are the customary fish plates 6, 6, in abutting engagement with the head 2 and flanges 4, and each provided on their inner sides with a hollowed out cavity, all of standard construction.

30 The fish plates and web 3 are provided with suitable holes for passage of the clamping bolts 7, having the usual tightening and loosening nuts, also standard.

35 I show, as in Figs. 1 and 2, the comparatively narrow transverse space or clearance 8, usually extending between the rails from top to bottom, through which space water from above may freely flow by gravity, for discharge upon the road bed below.

40 As shown in Figs. 1 and 4, the space between the rail web 3 and each outer fish plate 6 is occupied by two pairs of spaced apart lubricating pad units A, A; also endmost lubricant-retaining

45 and sealing non-lubricating units B, B, and middle non-lubricating intervening sealing units C. The latter, units C, like units B, B, are of a suitable somewhat pliable material and initial shape, to practically occupy and fit within the cavity at each side between the web 3 and each fish plate 6.

50 Each unit C, in addition to providing an abutting limiting bearing for the inner ends of lubricating units A, also closes effectually and seals both lateral portions of any vertical spaces

55

8, when the pair of units C are tightly clamped by the fish plates.

Units B and C are made of any suitable non-rigid material having sufficient pliability or resiliency subject to compression and deformation, for conformation with and closing entrance into such or any minute cavities or clearances. Such material may be sufficiently soft wood, wood pulp, or the like, without lubricant impregnation, and capable under pressure, of filling the cavities between the rail and the fish plates.

As indicated in dotted lines, as at b, the terminal units B, when first inserted, project slightly beyond the fish plates, and are finally driven in to final position as shown, and wired.

The units B thus act as plungers, and retaining dams, and force the lubricant A into all open spaces covered by the lubricating units.

Also, as indicated at 9, the pressure on unit C, effects closing of the space along each side of the minute space 8, in the manner of projecting ridges 9, as shown, thus sealing against passage of moisture.

The main source of lubrication is furnished by units A, which may be of any suitable lubricant as a heavy oil or grease, and an impregnating or holding body, for instance saw dust, wood pulp, etc., of a cartridge forming shape suitable for placement in position between the fish plates and the rail end portions.

Such construction may be made by means of corrugated paper 10, or the like, suitably perforated, and filled or invested with the lubricating medium.

I show in Fig. 7 such a roll ready for placement, which when subjected to pressure, is compressed to the final confined form, indicated in dotted lines. Otherwise, the same result may be secured by combining a series of corrugated or otherwise deformed packet or cell-providing deformed layers, for investing therewith of the lubricating medium, in the form of a slab, as in Fig. 8.

With either such lubricant carriers, or their equivalent, when the units A, B, and C are in proper location as assembled, followed by the fish plates, and the bolts and nuts are applied, the enclosed units are forced into proper positions, and then compressed by the bolts, to final tightness.

The result is to squeeze and force the lubricant into every corner and crevice, thus effectually closing off any access of moisture to exposed metal surfaces.

For the purpose of retaining the several units of the entire assembly in proper operative relation, each is provided with a small clearance groove 11 for insertion longitudinally of a continuous wire 12 at each side, finally turned over at the ends.

In assembling the joint, the outer retaining members B are shown as protruding beyond the fish plates at each end, as indicated in dotted lines.

When the fish plates, bolts and nuts, and the lubricant are loosely assembled, and the bolts are partly pushed up, these several members are driven into place, and the bolts are then pulled

to their final tightness, ready for operation of the track.

Thereupon, the already inserted wires 12 are turned over as at 13, firmly retaining the units B against outward movement.

I claim:

1. The combination with a conventional railway track joint wherein adjacent rail end portions are embraced at each side beyond their end junction zone by connecting fish plates, midway sealing units extending across said junction zone at each opposite side between the rail end portions and the fish plates, endmost sealing units between the terminal ends of the fish plates and the rails, and lubricating pads between the midway sealing units and the endmost sealing units.

2. The combination with a conventional railway track joint wherein adjacent rail end portions are embraced at each side beyond their end junction zone by connecting fish plates, midway sealing units extending across said junction zone at each opposite side between the rail end portions and the fish plates, endmost sealing units between the terminal ends of the fish plates and the rails, lubricating pads between the midway sealing units and the endmost sealing units,

20 25 and means connecting the fish plates and rails exerting pressure on the lubricating pads.

3. The combination with a conventional railway track joint wherein adjacent rail end portions are embraced at each side beyond their end junction zone by connecting fish plates, midway sealing units extending across said junction zone at each opposite side between the rail end portions and the fish plates, endmost sealing units between the terminal ends of the fish plates and the rails, lubricating pads between the midway sealing units and the endmost sealing units, and bolts connecting the fish plates and extending through the lubricating pads.

4. The combination with a conventional railway track joint wherein adjacent rail end portions are embraced at each side beyond their end junction zone and an intervening open joint space by connecting fish plates, midway sealing units extending across such space at each opposite side between the rail end portions and the fish plates, endmost sealing units between the terminal ends of the fish plates and the rails, lubricating pads between the midway sealing units and the endmost sealing units, and means connecting the fish plates and rails exerting pressure on the lubricating pads.
